UNITED STATES PATENT OFFICE.

JOHN A. GOSNELL, OF NASHVILLE, ARKANSAS.

THREAD AND BUTTONHOLE CUTTER FOR THIMBLES.

No. 824,925.

Specification of Letters Patent.

Patented July 3, 1906.

Application filed November 18, 1905. Serial No. 288,069.

To all whom it may concern:

Be it known that I, JOHN A. GOSNELL, a citizen of the United States, residing at Nashville, in the county of Howard and State of Arkansas, have invented new and useful Improvements in Thread and Buttonhole Cutters for Thimbles, of which the following is a specification.

My invention relates to improvements in thimbles.

The object of my improvements is to produce a simple, practical, and durable device for cutting thread and buttonholes; and it consists in attaching a sheathed steel blade either between the inner and outer lining of the thimble or attaching same to the outside of the thimble, as shown in the accompanying drawings, of which—

Figure 1 is a perspective view of a thimble with invention attached thereto, also in perspective and showing the blade extended. Fig. 2 is an elevation of a thimble with a face view of my invention attached thereto, the blade extended. Fig. 3 is an elevation of a thimble with a face view of my invention attached thereto, the blade sheathed. Fig. 4 is a view of a thimble and an edge view of my invention with the blade extended. Fig. 5 is a detail view showing the inner face of the sheath. Fig. 6 is a detail view showing a face view of the spring. Fig. 7 is a view showing the sheath, spring, and blade assembled. Fig. 8 is a face view of the blade.

My invention is described as follows:

35 The numeral 1 represents a thimble which may be made or used with or without a top. 2 is sheath attached to the side of the thimble or may be made integral therewith, open at the top and provided with guides 3 to hold the blade in place. Said sheath is provided near its center with a perforation 4. Situated in said sheath is a flat spring 5, having near its center a perforation 6, corresponding to said perforation 4. Said spring is secured in said sheath at its lower end by means of a clamp, rivet, or other device and is so constructed that its upper end will bear against the handle 7 of the blade 8. The said handle is provided with an elongated slot 9. Said handle is situated between the inner face of the sheath 2 and the spring 5, the blade 8 being adapted to run up and down in the guides 3. A bolt 10 has its inner end riveted or otherwise secured in the per-

foration of the spring 5 and extends outwardly through the slot 9 of the handle 7 of the blade 8 and then through the perforation 4 of the sheath 2, its end extending a little beyond the outer face of said sheath, and to the outer end of said bolt is secured a button 11. 55 60

My invention is operated as follows: When said button is pressed and the thimble turned down, the blade 8 is released and falls into position for use, as shown in Figs. 1, 2, and 4, and when the button is pressed and the thimble held in an upright position the blade falls back into said sheath, as shown in Fig. 3, and is concealed thereby and out of the way. The thimble and sheath may be cast in one piece or the sheath may be secured to the thimble 70 by soldering or other suitable means.

Having described my invention, what I claim as new, and desire to secure by Letters Patent, is—

1. The combination of a thimble 1, a sheath 2, secured to the thimble, and provided at its upper end with guides 3; a blade 8, provided with a slotted handle 7, working in said sheath and the blade in said guides; a spring 5, secured in said sheath, its upper end adapted to press against the face of said handle; bolt 10, having its inner end secured in a perforation in said spring, said bolt passing outwardly through slot 9, of said handle and through a perforation 4, in said sheath, and a button 11, secured on the outer end of said bolt, substantially as shown and described for the purposes set forth. 80 85

2. In combination with a thimble, a sheath secured to the same; a blade and handle adapted to work in and out of said sheath; a spring, secured at its lower end to the lower end of said sheath, its upper end adapted to press against the handle of said blade; a bolt, secured to said spring, passing through a slot of said handle and a perforation in said sheath, and a button secured in the outer end of said bolt, said bolt adapted to release the pressure of said spring against said handle, substantially as shown and described and for the purposes set forth. 90 95 100

In testimony whereof I affix my signature in presence of two subscribing witnesses.

JOHN A. GOSNELL.
